UNITED STATES PATENT OFFICE.

WILLIAM B. HAYDEN, OF NEW YORK, N. Y.

ELECTRICAL SPARKING DEVICE FOR EXPLOSIVE-ENGINES.

No. 870,954.

Specification of Letters Patent.

Patented Nov. 12, 1907.

Application filed June 12, 1906. Serial No. 321,394.

To all whom it may concern:

Be it known that I, WILLIAM B. HAYDEN, a citizen of the United States, residing at New York, in the county of New York and State of New York, have invented 5
5 new and useful Improvements in Electrical Sparking Devices for Explosive-Engines, of which the following is a specification.

This invention relates to electrical sparking devices for explosive engines, and aims to provide a device of 10 such class in a manner as hereinafter set forth, with electrically-operated means for moving an electrode to and from contact with another electrode, both of which are in a spark circuit, thereby creating the ignition spark. The circuit for operating the said means, which 15 is termed the main circuit, communicates with a single source of electrical energy while the spark circuit communicates with two sources of supply, one of which is the source for the main circuit. The main circuit is opened and closed during the operation of the engine by 20 the timing device or the circuit-making and breaking means carried by the engine, while the spark circuit is opened and closed owing to the actuation by the electrically-operated means, of a movable electrode which intermittently engages with a fixed electrode, thereby 25 creating the ignition sparks.

The invention further aims to provide the device with means to form what may be termed a starting circuit for initially throwing into operation said electrically-operated means, forming an ignition spark, thereby 30 igniting the explosive mixture in the combustion chamber of the engine, causing the explosion of such mixture and the operation of the engine; consequently causing the intermittent operation of the timing device or circuit-making and breaking means carried by the engine, 35 thereby creating the ignition sparks. The said starting circuit when closed so as to create the spark, owing to the actuation by the electrically-operated means of the movable electrode, overcomes the necessity of cranking or turning the engine over so as to cause the closing of 40 the main circuit, which would be the case if the means to constitute the starting circuit were dispensed with, the source of supply for the starting circuit being independent of the source of supply for the main circuit or the spark circuit.

45 The sparking device is particularly designed for use in connection with motor vehicles or motor boats, although it is adapted for any usages for which it may be found applicable. When used for a motor vehicle or motor boat, the closing of the starting circuit enables 50 the operator to readily start the engine without any inconvenience, as is generally the case at present.

The invention further comprises in its construction a plug set up in such manner that the movable parts

thereof can be kept in a state of lubrication owing to the fact that the bearings for the said movable parts are arranged away from the heat of combustion in the cylinder of the engine. 55

The invention further aims to provide an electrical sparking device for explosive engines which shall be extremely simple in its construction, readily positioned 60 with respect to the cylinder of the engine, efficient in its use and operation, strong, durable, obtaining an intensified ignition spark, easily set up in operative position, requiring no complicated wiring, compact, enabling an operator to obtain what may be termed the 65 initial spark, in a convenient manner and comparatively inexpensive to manufacture.

With the foregoing and other objects in view, the invention consists of the novel construction, combination and arrangement of parts hereinafter more specifically 70 described and illustrated in the accompanying drawings, which form a part of this specification, and wherein is shown the preferred embodiment of the invention; but it is to be understood that changes, variations and modifications can be resorted to which come within the 75 scope of the claims hereunto appended.

In describing the invention in detail, reference is had to the accompanying drawings, wherein like reference characters denote corresponding parts throughout the several views, and in which:

Figure 1 is a side elevation of a sparking device in accordance with this invention, with the circuit connections removed; Fig. 2 is a top plan; Fig. 3 is a section on line 3—3, Fig. 2; Fig. 4 is a section on line 4—4, Fig. 2; Fig. 5 is a perspective view of a movable electrode and shifting means therefor, the parts being disassembled, and Fig. 6 is a diagrammatical view of a sparking device in accordance with this invention, showing the circuit connections.

An electrical sparking device for explosive engines 90 in accordance with this invention, comprises a sectional hollow plug open at one end and closed at its other end, the inner or open section being indicated by the reference character 1, and the outer or closed section indicated by the reference character 2. The sec- 95

tion 1 is open from end to end, is exteriorly screw-threaded, as at 3, and at one end is provided with a protuberance 4 which is slotted to receive a contact point 5, preferably constructed of platinum. The protuberance 4 is arranged at the lower portion of the section 1, 100 and the said protuberance 4 with the contact point 5 forms a fixed electrode. The section 1 is adapted to be screwed into the engine cylinder 6 so that the fixed electrode will project into the combustion chamber of the engine and co-operate with a vibratory electrode to 105 be hereinafter referred to, said vibratory electrode also

projecting into the combustion chamber of the engine. Holdfast means, as at 7, is provided upon the section 1 which abuts against the cylinder 6 so as to prevent the loosening of the section 1. The outer end of the section 1 is formed with a plurality of apertured ears or lugs 8, for a purpose to be hereinafter referred to. The section 2 of the plug has its outer end closed and its inner end open, and the said section 2 is hollow and provided with apertured lugs or protuberances 9 of the same contour as the apertured ears or lugs 8. The section 2 is adapted to be secured to the section 1 through the medium of the holdfast devices 10 extending through the apertured ears 8 and 9, and the two sections 1, 2 are insulated from one another through the medium of the insulating material 11 which is interposed between the inner ends of the said sections and clamped between the same by the holdfast devices 10. Any suitable form of insulating material may be employed. Although the sections 1, 2 are provided with apertured ears or lugs which receive holdfast devices for connecting said sections with one another, yet any other suitable means for this purpose can be employed, and although the sections 1 and 2 are shown substantially square in contour, yet the same may be of any suitable shape. The section 2 is provided at one side with an opening closed by a removable plug 12. By such an arrangement, access can be had to the interior of the section 2 for cleaning it, or for other purposes.

The reference character 13 denotes an electro magnetic device which is suspended in close proximity to the closed end of the section 2 of the plug, and the said device 13 is suspended through the medium of a casing 14 which is suitably connected to the device 13; and the casing 14 is formed with an arm 15 secured upon the section 1 by the holdfast devices 16 and provided with a vertically-extending portion 17, to which binding posts 18, 19 are connected but insulated therefrom. From the post 18 leads the wire 21 to the magnet, and from the magnet to the post 19 lead the wire 20. Leading from the electrical source 22 to the post 18, is a circuit wire 23 and leading from the post 19 to the electrical source 22 is a circuit wire 24. Interposed in the circuit wire 23 is the timing or circuit-making and breaking device 25 which is carried by the engine. Interposed in the circuit wire 23 is a suitable switch 26. The armature of the magnetic device is indicated by the reference character 27, and is provided with a depending arm 28 carrying an adjustable lifting screw 29, the function of which will be hereinafter referred to; and the casing 14 is formed with a depending arm 30 carrying an adjustable set screw 31 for limiting the downward movement of the armature. The armature 27 is hinged as at 32.

The vibratory electrode consists of an elongated arm 33 split at one end through which extends a contact point 34 preferably formed of platinum and co-operating with the contact point 5. The arm 33 extends from a point in the section 2 of the plug through the section 1 of the plug, is arranged within the said section so it will not contact with either of them, and has that end which is positioned in the section 2 suitably connected, as at 35, to the inner end of a rock-shaft 36 which is mounted in one wall of the section 2 and in the bearing arm 37 which projects laterally from one side of the sec-

tion 2. The inner end of the shaft 36 is provided with 65 a bifurcated head 38 having a screw-threaded recess 38^a, and the said bifurcated head 38 is adapted to receive one end of the arm 33, the latter being provided with an opening 38^b through which extends a holdfast means 38^c, the said holdfast means 38^c engaging in the 70 screw-threaded recess 38^a, thereby securing arm 33 to the head 38 of the shaft 36. The head 38 bears against the inner wall of the section 2 and acts as a means to prevent leakage through the opening in the section 2 in which is mounted the shaft 36. Fixed to the rock-shaft 36, through the medium of a pin 38^d is a sleeve 40 recessed, as at 40^a, to form a pocket to receive a spring 40^b which also engages in a pocket formed in the outer face of the side wall of the section 2 through which the shaft 36 extends. The spring 40^b acts as a means to retain the head 38 against the wall of the section 2. The sleeve 40^a is provided with a longitudinally-extending actuating arm 41 which is of such length as to extend over the adjustable lifting screw 29 so that when the armature 27 is elevated, the screw 29 will engage the 85 arm 41 and rock the shaft 36, thereby shifting the movable electrode against the fixed electrode. The electrodes are normally retained separated through the medium of an adjustable compression spring 42 mounted upon the arm 41 and engaged by an adjustable member 43 carried by the arm 15, the latter being provided with an offset to receive the said member 43. The tension of the spring 42 is regulated through the medium of the adjustable member 43.

The main circuit is formed by the circuit wire 23 95 from the electrical source to binding post 18, branch wire 21 to magnet 13, through the magnet, thence to binding post 19 and circuit wire 24 to source 22. The timing or circuit-making and breaking device 25 and switch 26, as before stated, are interposed in the circuit wire 23.

With the electrical source 22 is coupled, as at 22^a, an electrical source 44. The two sources of supply 22 and 44 are in the sparking circuit and the said circuit is formed by the coupling 22^a, and circuit wire 45 105 leading to a non-vibrating coil 46. From the coil 46 leads a branch wire 47 to the engine bed 48, through the engine bed 48 to fixed electrode, through vibratory electrode, section 2, binding post 48^a, circuit wire 49, part of wire 24, thence to coupling 22^a. The 110 interposition of the non-vibrating coil 46 acts as a means to intensify the spark, as will be evident. The non-vibrating coil may be of any suitable construction.

From the arrangement of the circuits it will be evident that the main circuit is somewhat weaker than 115 the sparking circuit as it embodies but a single electrical source, consequently as the sparking circuit embodies the two-fold source of electrical energy, the energy will be greater than the main circuit. As the power necessary to energize the magnet 13 need not 120 be as great as that used for forming a spark, owing to the arrangement of the circuits with respect to the two-fold source of supply, a saving in current is evident as the sparking circuit communicates only with a single source of electrical energy, such source being sufficient to energize the magnet 13 to shift the vibratory electrode to form the spark. By employing the separate circuit for energizing the magnet, the spark 125

will be made slightly after the timing or circuit-making and breaking device is operated, or in other words, the spark will not be made until the main circuit is broken. The plug when set up has only a portion of the screw-threaded section 1 extending in the cylinder, the section 2 being in a position at a point removed from the cylinder and by such arrangement, it is evident that the movable parts of the plug are positioned at a point removed from the heat of combustion within the cylinder; consequently these movable parts can be kept lubricated at all times.

To overcome the cranking or turning over of the engine so as to bring the elements of the timing or circuit-making and breaking device into contact to 15 form an initial spark, a starting circuit is provided which is independent of the main circuit, and which is adapted to energize the magnet so as to form the initial spark. This starting circuit comprises a switch in the form of an ordinary push-button, the movable 20 member of which is indicated by the reference character 50, and the fixed member by the reference character 51. The push-button is interposed in the circuit wire connection 52, leading from an electrical source 53 to the circuit wire 23, and leading from the 25 circuit wire 23 is a circuit wire 54 which terminates at the electrical source 53. It will be evident that when the push-button is operated in one direction, the starting circuit will be formed, energizing the magnet, operating the movable electrode to form the 30 initial spark, causing thereby the explosion of the mixture in the combustion chamber of the engine, operating the engine and throwing into intermittent operation the timing or circuit-making and breaking device. The starting circuit is closed manually by 35 the operator when desired.

It is thought that the operation of the sparking device can be understood from the foregoing description, taken in connection with the accompanying drawings, but it will be stated that when the electro-magnetic device is energized, the armature 27 will be attracted; consequently moving the contact points 5 and 34 together. When the magnet is deenergized, the action of the spring 42 will cause the contacts 5 and 34 to separate, thereby creating a spark. The 40 energizing and deenergizing of the magnet 13 will be had while the engine is running, and owing to the action of the movable electrode with respect to the fixed electrode, it will be evident that the sparking circuit will be intermittently closed and opened; 45 consequently intermittently creating an ignition spark which will be intensified owing to the interposition of the soft core coil or non-vibrating coil, or what may be termed a primary current coil. The initial energizing of the magnet so as to form the initial spark is 50 had, as before stated, owing to the operation in one direction of the push-button, thereby closing the starting circuit which will remain in such condition until pressure is removed from the push button, this action breaking the starting circuit and causing the 55 spring 42 to come into play and separate the electrodes, thereby forming the initial spark for starting purposes.

The intermittent contacting of the points 5 and 34 60 keep them free from scale, soot or other foreign sub-

stances, insuring thereby perfect metallic connection 65 and certainty of ignition.

Having thus fully described my invention, what I claim as new and desire to secure by Letters Patent, is:

1. An electrical sparking device for explosive engines, comprising a two-fold electrical source, a pair of electrodes one of which is movable, an electro-magnetic device for operating said movable electrode to contact with the other electrode, circuit-forming means between said electro-magnetic device and one of the electric sources of said two-fold source, means for separating the electrodes, circuit-forming means between said electrodes and said two-fold electrical source, another electrical source, and circuit-forming means between said device and the last mentioned electrical source. 70

2. An electrical sparking device for explosive engines, comprising a two-fold electrical source, a pair of electrodes, one of which is movable, an electro-magnetic device independent of the engine frame for operating said movable electrode to contact with the other electrode, circuit connections independent of the engine frame and between 75 said electro-magnetic device and one of the electrical sources of said two-fold source, means for separating the electrodes, circuit connections between said electrodes and said two-fold electrical source, another electrical source, circuit connections between said device and the last-mentioned electrical source, and a non-vibrating coil interposed in said circuit forming means between the electrodes and said two-fold electrical source. 80

3. An electrical sparking device for explosive engines comprising a bridged two-fold electrical source, another electrical source independent of said two-fold electrical source, a pair of electrodes, sparking circuit connections between said electrodes and said two-fold electrical source, means for causing the contact of the electrodes, thereby closing the sparking circuit, circuit connections between 90 said means and one of the sources of said two-fold source, a circuit-making and breaking device in said last-mentioned circuit connections, circuit connections between said means and said other source of electrical energy, and a circuit-making and breaking device in said last-mentioned circuit 95 connections. 100

4. An electrical sparking device for explosive engines comprising a bridged two-fold electrical source, another electrical source independent of said two-fold source, a pair of electrodes, sparking circuit connections between 105 said electrodes and said two-fold electrical source, means for causing the contact of the electrodes, thereby closing the sparking circuit, circuit connections independent of the engine frame and between said means and one of the sources of said two-fold source, a circuit-making and breaking device in said last-mentioned circuit connections, circuit connections between said means and said other source of electrical energy, a circuit-making and breaking device in said last-mentioned circuit connections, and a non-vibrating coil in said sparking circuit connections. 110

5. An electrical sparking device for explosive engines, comprising a hollow plug provided with a fixed electrode, a rock-shaft mounted in said plug, projecting from one side thereof and having means to prevent leakage through that side of the plug through which the shaft extends, an 115 arm carried by the rock shaft a movable electrode connected to said rock-shaft and cooperating with said fixed electrode, an armature, a magnet cooperating with the armature, means carried by the plug and engaging the said arm for normally retaining the two electrodes out of 120 contact, circuit connections cooperating with the magnet leading to a single electrical source, circuit connections cooperating with the electrodes and leading to a two-fold electrical source, and circuit connections cooperating with the magnet leading to an electrical source independent of 125 the other sources. 130

6. An electrical sparking device for explosive engines comprising a sparking circuit embodying two electrodes and further comprising a non-vibrating coil, a two-fold source of electrical energy in the sparking circuit a main 135 circuit for causing the contact of the electrodes, said main circuit independent of the engine frame and connected to

- one of the sources of said two-fold source, and a starting circuit for causing the initial contact of the electrodes, said starting circuit independent of the engine frame and communicating with another electrical source.
5. 7. An electrical sparking device comprising a sparking circuit embodying two electrodes, a two-fold electrical source in the sparking circuit a main circuit for causing the contact of the electrodes, said main circuit independent of the engine frame and communicating with one of the 10 sources of said two-fold source, and a starting circuit for causing the initial contact of the electrodes, said starting circuit independent of the engine frame.
8. An electrical sparking device for explosive engines comprising a hollow plug provided with a fixed electrode, 15 a rock-shaft mounted in one side of said plug and having its inner end formed with a head bearing against the wall of the plug and constituting a means to prevent leakage through said wall, an arm carried by the rock shaft, a movable electrode carried by said shaft and co-operating with the fixed electrode, an armature, a magnet co-operating with the armature, means co-operating with the armature for rocking said shaft, means carried by the plug and engaging the said arm for normally holding the electrodes out of contact.
- 20 9. An electrical sparking device for explosive engines comprising a hollow plug provided with a fixed electrode, a rock-shaft mounted in one side of said plug and having its inner end formed with a head bearing against the wall of the plug and constituting a means to prevent leakage through said wall, an arm carried by the rock shaft a movable electrode carried by said shaft and co-operating with the fixed electrode, an armature, a magnet co-operating with the armature, means co-operating with the armature for rocking said shaft, means carried by the 25 plug and engaging the said arm for normally holding the electrodes out of contact, circuit-forming connections co-operating with the magnet and independent of the engine bed, and circuit-forming means co-operating with said electrodes.
10. An electrical sparking device for explosive engines comprising a hollow plug provided with a fixed electrode, a rock-shaft mounted in one side of said plug and having its inner end formed with a head bearing against the wall of the plug and constituting a means to prevent 30 leakage through said wall, an arm carried by the rock shaft, a movable electrode carried by said shaft and co-operating with the fixed electrode, an armature, a magnet co-operating with the armature, means co-operating with the armature for rocking said shaft, means carried by the plug and engaging the said arm for normally holding the electrodes out of contact, circuit-forming connections co-operating with the magnet and independent of the engine bed, and circuit-forming means co-operating with said 35 electrodes.
11. An electrical sparking device for explosive engines comprising a hollow plug carrying a fixed electrode, a rock-shaft mounted in said plug and having a head upon one end thereof adapted to bear against the plug and act as a means to prevent leakage, said shaft projecting laterally from the plug, an arm carried by the rock shaft a movable electrode carried by said shaft and co-operating with said fixed electrode, an armature, an arm carried thereby and provided with a lifting screw, a magnet co-operating with the armature, means carried by the shaft and adapted 40 to be engaged by said screw for rocking the shaft when the magnet is energized, and means carried by the plug and engaging the said arm for normally holding the electrodes out of contact.
12. An electrical sparking device for explosive engines comprising a hollow plug carrying a fixed electrode, a rock-shaft mounted in said plug and having a head upon one end thereof adapted to bear against the plug and act as a means to prevent leakage, said shaft projecting laterally from the plug, an arm carried by the rock shaft, a movable electrode carried by said shaft and co-operating with said fixed electrode, an armature, an arm carried thereby and provided with a lifting screw, a magnet co-operating with the armature, means carried by the shaft and adapted 45 to be engaged by said screw for rocking the shaft when the magnet is energized, means carried by the plug and engaging the said arm for normally holding the electrodes out of contact.
13. An electrical sparking device for explosive engines comprising a hollow plug carrying a fixed electrode, a rock-shaft mounted in said plug and having a head upon one end thereof adapted to bear against the plug and act as a means to prevent leakage, said shaft projecting laterally from the plug, an arm carried by said rock shaft, a movable electrode carried by said shaft and co-operating with said fixed electrode, an armature, an arm carried thereby and provided with a lifting screw, a magnet co-operating with the armature, means carried by the shaft and adapted 50 to be engaged by said screw for rocking the shaft when the magnet is energized, means carried by the plug and engaging the said arm for normally holding the electrodes apart, circuit-forming connections co-operating with the electrodes, and circuit-forming connections co-operating with the magnet and independent of the engine frame.
14. In an explosive engine, the combination with the engine frame, of an electrical sparking device supported by said frame and comprising a fixed and a movable electrode, a magnetic device for intermittently actuating said movable electrode to contact with the fixed electrode, a two-fold electrical source, means for coupling said sources together, circuit wire connections leading from one of said sources to said magnetic device, a circuit wire leading 55 from said connections to said movable electrode, circuit wire connections leading from said coupling means to said magnetic device, and circuit wire connections leading from the other of said sources to the engine frame.
15. In an explosive engine, the combination with the engine frame, of an electrical sparking device supported by said frame and comprising a fixed and a movable electrode, a magnetic device for intermittently actuating said movable electrode to contact with the fixed electrode, a two-fold electrical source, means for coupling said sources together, circuit wire connections leading from one of said sources to said magnetic device, a circuit wire leading 60 from said connections to said movable electrode, circuit wire connections leading from said coupling means to said magnetic device, circuit wire connections leading from the other of said sources to the engine frame, and a non-vibrating coil interposed in said last mentioned circuit wire connections.
16. In an explosive engine, the combination with the engine frame, of an electrical sparking device supported by said frame and comprising a fixed and a movable electrode, a magnetic device for actuating the movable electrode to contact with the fixed electrode, two sources of electrical energy, means for coupling said sources together, another source of said electrical energy independent of the double source, circuit wire connections between one of the sources of said double source and said magnetic device, a circuit wire connection leading from said circuit wire connections to the movable electrode, circuit wire connections leading from said coupling means to said magnetic device, circuit wire connections leading from the other source of said double source to the engine frame, and circuit wire connections between said independent source and the connections between the single source of said double source and the magnetic device.
17. In an explosive engine, the combination with the engine frame, of an electrical sparking device supported by the frame and comprising a fixed and a movable electrode, an electro-magnetic device for intermittently causing the contact of the electrodes, a two-fold electrical source, means for coupling said sources together, a circuit wire leading from said coupling means to said magnetic device, a circuit wire leading from one of said sources to said magnetic device, a circuit making and breaking device in said last mentioned circuit wire, a circuit wire leading from said last mentioned circuit wire to said movable electrode, and circuit wire connections leading from the other source of said two-fold sources to the engine frame.

18. In an explosive engine, the combination with the engine frame, of an electrical sparking device supported thereby and comprising a pair of electrodes, means for intermittently contacting the electrodes, a two-fold source of electrical energy, circuit wire connections between one of the sources of said two-fold source and said means, circuit-making and breaking means in said connections, a circuit wire leading from said connections to one of said electrodes, circuit connections leading from the other 10 source of said two-fold source to the engine frame, another

source of electrical energy, and circuit connections between said last mentioned source and the circuit connections between the means for contacting the electrodes and one of the sources of said two-fold source.

In testimony whereof I have hereunto set my hand in 15 presence of two subscribing witnesses.

WILLIAM B. HAYDEN.
